UNITED STATES PATENT OFFICE.

THOMAS P. ROY, OF SEATTLE, WASHINGTON.

UNIVERSAL SQUARE.

SPECIFICATION forming part of Letters Patent No. 746,384, dated December 8, 1903.

Application filed August 14, 1902. Serial No. 119,671. (No model.)

To all whom it may concern:

Be it known that I, THOMAS P. ROY, a citizen of the United States of America, and a resident of the city of Seattle, in the county of King and State of Washington, have invented certain new and useful Improvements in Universal Squares, of which the following is a specification.

My invention relates to improvements in universal squares and has special reference to an instrument of this nature which is especially adapted for laying off cuts for bevel-joints.

Among numerous objects attained by this invention and readily understood from the following specification and accompanying drawings included as a part thereof is the production of a universal square of simplified and inexpensive construction and which embodies essential features of adjustment, adaptability, and general utility, which greatly facilitates the measuring of corners and angles in frames or the like and the accurate marking of the finishing material for the cuts required to fit same to the frame.

The above-mentioned and numerous other objects equally as desirable are attained by the construction, combination, and arrangement of parts as disclosed on the accompanying drawings, set forth in this specification, and succinctly pointed out in the appended claims.

With reference to the drawings filed herewith and bearing like reference characters for corresponding parts throughout, Figure 1 is a perspective view of my improved square shown with the arms adjusted to measure an outside angle and the movable tongue projected, and Fig. 2 is a plan view of the device on enlarged scale with the shank and head shown in longitudinal section and the arms set for measuring an inside angle and the tongue shown partly projected.

This invention includes a shank, as 10, oppositely-disposed angle embracing-arms 12, pivotally mounted on said shank, at one end thereof, by pivots 9, seated in ears 8 on opposite sides of the shank, a movable tongue 14, arranged on said shank for projection and retraction relatively to the end thereof at which said arms are connected, and suitable arm adjusting and securing means adapted

to swing the arms on their pivots, and thereby open and close them relatively to each other and lock them in adjusted position.

55

As now embodied, shank 10 is rendered substantially rectangular in cross-section and of considerable length and is formed with a longitudinally-disposed guideway, as 15, extending rearwardly from the head end, adapted to conveniently adjustably mount the tongue 14 on the shank and consisting in the present embodiment of an elongated recess or bore of suitable length to receive the tongue completely when retracted. This tongue 65 preferably consists of a broad thin blade which is formed with a longitudinally-disposed slot 16, arranged substantially midway the width of the face and extending throughout the greater portion of its length, and the 70 guideway 15 is formed of suitable size in cross-section to slidably receive said tongue snugly and is preferably so disposed that the slot 16 will lie directly between the pivots of arms 12 when the tongue is projected and 75 serve as a guide for marking relatively to the arms when they are set at any desired angle.

As now considered arms 12 are conveniently moved by means of a head, as 17, which is slidably mounted on shank 10 and suitably 80 operatively connected to said arms by connecting-rods, as 18, which are pivotally connected at one end to respective arms at points substantially midway their length by suitable pivots 19, seated in suitable ears 22, 85 formed on said arms, and are likewise pivotally connected at the opposite ends to the head by pivots 20, seated in ears 23, arranged on the side edges of said head, so as said head is adjusted along the shank these arms will 90 be equally opened or closed relatively to each other and may thereby be conveniently and expeditiously adjusted to any desired angle.

In the present instance a thumb-screw, as 21, is engaged in a suitable screw-threaded aperture formed in the wall of head 17 at a convenient point to cause the end of the screw to impinge the shank when properly manipulated, and thereby secure the head, and consequently the arms 14, at any desired point, 95 and suitable graduation-marks are placed at proper intervals on one side surface of the shank to indicate the number of degrees between the arms, and like marks are placed on 100

one of the other side surfaces to indicate the number of degrees between each of said arms and the marking-slot in tongue 14.

In the present instance shank 10 is formed 5 with laterally-projecting ears 8 at the forward end, which are arranged on opposite side edges and have suitable apertures adapted to act as bearings for pivots, as 9, by which the arms 12 are mounted thereon, and lugs, as 10 25, are placed on the back surfaces of arms 12 and have apertures therein to receive the pivots 19, and a suitable keeper, as a pin 26, is disposed across guideway 15 through slot 16 at the forward end of shank 10 to keep 15 tongue 14 from leaving the recess.

This instrument may be used in numerous ways to measure angles, lay off the lines of cuts for simple and complex joints and the lines of cuts for finishing material in wood 20 and iron working, and may also be employed as a center-square or as a T-square. When employed to measure angles, the outer surfaces of arms 12 are brought to the lines or surfaces forming the angle and the degrees 25 read from the graduations on shank 15, and when desired to lay off lines of cuts for boards or timbers to meet at the angle thus measured tongue 14 is projected and the instrument is placed on the board or timber with 30 the face of one arm against one side surface, when the tongue will be in proper position to make the line of cut by using the slot 16 as a guide. This is equally true for either inside or outside angles, and when desired to 35 employ the device as a T-square the arms 12 are simply set in direct alinement with each other to serve as the head, and the tongue 14 is then projected and employed as the blade.

Having thus described my invention, what 40 I claim as new, and desire to secure by Letters Patent of the United States of America, is—
1. In an instrument of the nature indicated; a shank, oppositely-disposed, angle embracing-arms pivotally mounted thereon at one 45 end, and an angle dividing-tongue movably mounted on said shank for projection rela-

tively to said end and having a longitudinally-disposed marking-slot.

2. In an instrument of the nature indicated; a shank, oppositely-disposed angle embracing-arms pivotally mounted thereon at one end, means to secure said arms in adjusted positions and an angle dividing-tongue movably mounted on said shank for projection and retraction relatively to said end and having a longitudinally-disposed marking-slot. 55

3. In an instrument of the nature indicated; a shank, oppositely-disposed arms pivotally mounted thereon at one end, a head slidably mounted on said shank, oppositely-disposed rods pivoted to said head and to respective arms, means to lock the head to the shank and a tongue slidably mounted on said shank. 60

4. In an instrument of the nature indicated; an elongated shank, oppositely-disposed arms pivotally connected to one extremity thereof, a head slidably mounted on the shank, oppositely-disposed connecting-rods pivoted to said head and to respective arms, means to lock the head to the shank, and a longitudinally-disposed tongue slidably mounted on 65 said shank. 70

5. In an instrument of the nature indicated; an elongated shank, having a longitudinally-disposed recess extending rearwardly from 75 one end and having ears on opposite sides at said end, oppositely-disposed arms pivoted at one end to said ears a head slidably on said shank, oppositely-disposed connecting-rods pivoted to said head and to respective arms substantially midway their length, means to lock said head to the shank, and a tongue slidably mounted in said recess and having a longitudinally-disposed marking-slot. 80

Signed at Seattle, Washington, this 14th 85 day of July, 1902.

THOMAS ^{his} X P. ROY.
